UNITED STATES PATENT OFFICE.

THOMAS COX, OF GLOSTER, MONTANA TERRITORY.

MINER'S CANDLESTICK.

SPECIFICATION forming part of Letters Patent No. 321,798; dated July 7, 1885.

Application filed January 7, 1885. (No model.)

To all whom it may concern:

Be it known that I, THOMAS COX, of Glos-
ter, in the county of Lewis and Clark, and in
the Territory of Montana, have invented a
5 new and Improved Miner's Candlestick, of
which the following is a full, clear, and exact
description.

My invention relates to improvements in
miners' candlesticks; and it consists in the pe-
10 culiar construction and arrangement of parts,
as hereinafter fully described, and pointed
out in the claim.

Reference is to be had to the accompanying
drawings, forming a part of this specification,
15 in which similar letters of reference indicate
corresponding parts in all the figures.

Figure 1 is a top view of the candlestick.
Fig. 2 is a side view. Fig. 3 is a cross-section
on the line $x x$, Fig. 2.
20 The holder consists of the socket-piece a ,
which is formed with or attached upon a bar,
 b , that is sharpened at one end, and at the
other end the bar is provided with a handle, c .
Upon the socket-piece a is a hinged cover, d ,
25 which is provided with a handle, d' . A.
Spring e tends to close the cover of the socket.
Beneath the socket-piece is a spring-holder, f ,
consisting of a flat piece of metal bent in cir-
30 cular form, so as to form a spring for grasp-
ing the lower end of the candle. This holder

f is attached to the bar b by means of a pin
and staple at g , so that it can be removed. h
is a hook attached at one side of the bar b , for
use in suspending the candle-holder.

In using the candlestick it is held in the 35
desired place by the point of the bar b being
thrust into the heading or other place, or, if
more convenient, may be suspended by means
of the hook. The candle being inserted, the
cover d is held in an open position, as shown 40
in Fig. 2, and in case there is no person pres-
ent to attend to the lights the cover d will
close down as soon as the candle burns down
to the socket, thereby extinguishing the flame
at once. This prevents the candle from burn- 45
ing down and heating the socket, and thereby
dropping out, with the liability of setting fire
to any dry material that may be lying around.

Having thus fully described my invention, I
claim as new and desire to secure by Letters 50
Patent—

The combination, with a miner's candle-
stick, of the spring-holder f , detachably se-
cured to the under surface of the same, below
the candle-socket, substantially as herein 55
shown and described.

THOMAS COX.
